CLAIM

The ornamental design for a table top, as shown and described.

DESCRIPTION

FIG. 1 is a top perspective view of half of a table top in accordance with my invention, the other half being identical;

FIG. 2 is a front elevational view thereof;

FIG. 3 is a rear elevational view thereof;

FIG. 4 is a left side view thereof, the right side being a mirror image thereof;

FIG. 5 is a top plan view thereof;

FIG. 6 is a bottom plan view thereof; and,

FIG. 7 is a perspective view, illustrating two identical halves of a table top in accordance with the invention, joined together to form a table.

FIG. 7 illustrates the table top formed on a conventional base, shown in broken lines which along with fastening elements, also shown in broken lines which do not represent part of the invention, but merely represent environmental structure included only for illustrative purposes.
